ATTORNEYS

UNITED STATES PATENT OFFICE.

DANIEL W. SHOYER, OF NEW YORK, N. Y.

DESIGN FOR A HAMMOCK-VALANCE.

No. 38.418.

Specification for Design.

Patented Jan. 15, 1907.

Application filed December 13, 1906. Serial No. 347,735. Term of patent 3½ years.

To all whom it may concern:

Be it known that I, DANIEL W. SHOYER, a citizen of the United States of America, and a resident of the city of New York, (borough of Manhattan,) in the county and State of New York, have invented a new, original, and ornamental Design for a Hammock-Valance, reference being had to the accompanying drawing, in which a plan view of the fabric is shown.

I claim—

The ornamental design for a hammock-valance, as shown.

DANIEL W. SHOYER.
